UNITED STATES PATENT OFFICE.

RAYMOND A. GARDNER, OF LOS ANGELES, CALIFORNIA.

CAISSON-DREDGER.

No. 852,713.

Specification of Letters Patent.

Patented May 7, 1907.

Application filed October 1, 1906. Serial No. 337,032.

To all whom it may concern:

Be it known that I, RAYMOND A. GARDNER, a citizen of the United States, residing at Los Angeles, in the county of Los Angeles and State of California, have invented a new and useful Caisson-Dredger, of which the following is a specification.

This invention relates to caissons to be used for mining and cleaning up bed-rock under water through the use of compressed air and gravel pumps for pumping the matter under the level of the water.

This invention is applicable for use in various situations and includes apparatus for leveling the machine so as to bring the caisson in perpendicular position in order that it may be sunk.

The invention also includes a caisson of this description adapted to be moved over the ice or on land.

The main object of the invention is to provide means whereby the bed-rock of the placer can be readily cleaned by hand while under the level of the water.

Other objects of the invention may appear from the subjoined description.

The accompanying drawings illustrate the invention:

Figure 1 is a side elevation of a caisson dredger in position for operation. Fig. 2 is a plan of the same. Fig. 3 is a transverse vertical section on line x^3 , Figs. 1 and 2, looking left. Figs. 4 and 5 show the closed and open positions of the pump discharge. Figs. 6 and 7 show the open and closed positions respectively of the receptacle for holding the cleanings of the bed-rock.

1 designates a caisson having a compartment 2 at the bottom which terminates in a constricted neck or chamber 3 extending upward from the bottom of the compartment 2, and surrounded above by water compartments 4 and 4' occupying the space formed by the constricted neck portion 3. The neck or constricted portion 3 forms an air chamber between the air locks 5 and 6.

7 is a frame mounted on a platform 8 and extending around the caisson 1 and having mounted thereon supporting guides 9 between which racks 10 provided on opposite sides of the caisson are arranged to travel. 11 are pinions adapted to mesh with said racks 10, the same being operated by shafts 12 and gears 13, which latter gears are mounted on a countershaft 14, which shaft

in turn is operated by a pulley 15 and belt 16 connected to a motor or other driving power 17, such for instance as a steam engine or other form of motor. The motor 17 has a shaft 17' which is connected with the engine and capable of connection with an air pump, as seen at 19, the means for throwing said pump into rotative action with said shaft being illustrated at 18, and comprising a clutch. This pump is employed to draw up the dredged material through the flexible hose 22 extending in the caisson. A flexible tubing 20 extends through the water compartment 4 and through the submerged compartment 2 of the caisson 1; said tubing 20 being led over a roller 20' journaled in said frame 7 in order to facilitate the travel of the tubing in the descent of the caisson.

21 is a pipe connection in the caisson located in the compartment 4, and 22 designates a flexible hose in the caisson attached to the fitting 21 and provided at the bottom thereof with a grating 23.

24 is a winch for operating a cable 25 which may be used for shifting the machine from place to place by attaching the rope 25 to a dead-man and causing the cable to wind on the winch and thereby pull the entire structure on the runners 50 of the device.

26 is an electric generator for producing light and power.

27 designates an air pump, and 28 a storage tank for the air produced by the air pump, the latter being connected by pipe 29 in any manner, such for instance as reel 30, with a valve, hose or pipe 31 to supply air to the bottom compartment 2 of the caisson. 32, 33, are the valves of the air pipe 31 in the caisson. The chamber formed between the air locks 5 and 6 is supplied with air by means of the pipe 31 extending through said compartment, the inlet of the air into this chamber being controlled by valve 34 attached to a branch 35 of the pipe 31. The passage of air to the lower compartment is prevented by the valve 32, while the valve 34 admits the air into the air lock 3.

In order to provide for the accommodation of the workmen in descending with the caisson to carry out the work of dredging, I provide a folding platform 36 hinged or pivoted at 37, the two folds of the platform being supported by lugs 38 provided on the interior of the lower compartment of the caisson.

In the event of the caisson landing on very uneven ground, which is particularly the case in shallow waters, and which would have a tendency to place one end of said caisson on a level higher than the other end, I provide a flexible apron 39 on the interior of the bottom of said caisson, said apron being secured to the caisson bottom by means of a metallic ring 40, and the free end of said apron being supported and held in place by pins 41. Thus, when unevenness in the formation of river or other bottoms is encountered, the apron is released from the supporting pins 41 and allowed to fall over the particular piece of ground which it is desired to clean or dredge, whereupon the air from the air compressor displaces the water and leaves the space within the apron perfectly free and dry for the operator to carry out his work. This apron is in the nature of a cylindrical extension provided on the end of the caisson and is designed primarily to be swung beyond the end of the caisson when the body portion of the caisson itself is unsuited for the accommodation of uneven bed rock. It is rigidly secured within the end of the caisson and when projected beyond the end of the same forms a cylindrical flexible inclosure into which the air is pumped and the water which may have entered, displaced by the equalization of the confined air with the pressure upon the outside.

42 is an outlet valve connected to the water compartment 4; this water compartment being provided particularly for the purpose of assisting the caisson in its descent. 43 represents a water inlet for said water compartment 4, the inlet being connected with any source of supply, which is immaterial in the construction of this particular form of device. As the gravel, detrital earth, or other fragments of rocks, are being sucked through the tubing 22 by means of the air pump, it enters, after its discharge through the valve-gate 44, into the sluice-box 45 arranged immediately at the discharge end of the suction-pipe 20". The valve-gate 44 is provided at the extremity of the tubing 20 in order to prevent the escape of the compressed air when the grating 23 of the tubing 22 is not submerged in water which would permit all of the air to escape. This valve-gate comprises a weighted member 46 having attached to it a valve cap 47 forming substantially a cone and consisting preferably of elastic or yielding material for the purpose of effecting a perfectly snug and tight joint at the extremity of the tubing 20. On the weighted member 46 is provided a pawl 48 extending rearwardly of the weighted member and adapted to exert its strain against the excessive pressure generated by the air pump when the suction-tube is submerged. This pawl engages a rack 49 secured to and made a part of the extreme end of the tubing 20.

When the grating 23 is submerged in water and is performing its work of delivering gravel, sand, etc., into the sluice-box, this valve is allowed to remain open in order to permit the gravel and sand to escape into the sluice box 45.

This invention is designed particularly for use in countries where intense cold prevails and the rivers are frozen from three to five feet in thickness, in which instance the runners 50 are called into play and designed to carry the entire platform containing the operating mechanism for dredging. The platform or base 8 is carried by the runners 50 by means of a ball-joint 51, swivel, or pivotal joint, as may be desired, in order to compensate for variations in the levels of the base with respect to the runners when uneven surfaces are encountered. The base is provided with a plurality of uprights 52 which are hollow and arranged to accommodate a piston or plunger 53 operating in the bores of said uprights 52. The means employed for operating these plungers or pistons 53 for leveling the base, constitute preferably pneumatic or fluid pressure means, in which instance the piston box,—which in this case is the upright 52 itself,—will be connected with a fluid pressure supply pipe 57 from the pump. When the fluid pressure is allowed to act on the pistons and to raise the base of the device, the swivels or ball joints 51, resting on the runners, are called into play, as is perfectly clear. The pipe being connected with the source of supply from the tank 28, affords means for causing the base to rise with respect to the pistons and the runners. This supply is controlled by the valve 58, and in order to independently control one of the uprights or pistons irrespectively of the others, the valves 59 are employed as expediency may require. 60 is an escape valve for permitting the exit of the fluid from the uprights when the normal position of the base is desired. These pistons are provided on all four uprights of the base, and in order to maintain said base in its determined position, quadrants 54 or any other locking means, are provided. In the case of quadrants, spring-actuated dogs 55 are employed to engage the notches 56 in the quadrants.

If it is desired to use this dredge and caisson on land, rollers 57 are attached to the runners, these rollers being swiveled so as to allow of the caisson assuming any position.

What I claim is:—

1. A caisson having a flexible apron at its end, and means for suspending said apron within said caisson.
2. Runners, a base on said runners, and a caisson carried by said base.
3. Runners, a base on said runners, a caisson carried by said base, and means for lowering and raising said caisson.
4. Runners, a base on said runners, a

caisson carried by said base, and geared means for lowering and raising said caisson.

5. Runners, a base on said runners, a caisson on said base, geared means for operating said caisson, and means for operating said geared means.

6. Runners, a base on said runners, a caisson carried by said base, means in operative relation to said caisson to cause the 10 same to lower and rise, and means for leveling said base.

7. Runners, a base on said runners, a caisson on said base, means in operative relation to said caisson to cause the same to 15 lower and rise, and means for leveling said base independently of said runners.

8. Runners, a base on said runners, a caisson on said base, means in operative relation to said caisson to cause the same to 20 lower and rise, and fluid pressure means for leveling said base.

9. Runners, a base on said runners, a caisson carried by said base, means in operative relation to said caisson to cause the 25 same to lower and rise, and means for leveling each end of said base independently of each other.

10. The combination with a base and runners, of means interposed between said runners and base for leveling said base with respect to uneven earthly formations, a frame carried by said base, a caisson in said frame having racks, supports carried by said frame and bearing against said racks to aline said 35 caisson, means engaging said racks for raising and lowering said caisson, a suction pipe extending through said caisson, and means for preventing the escape of the compressed air from said suction pipe.

40 11. The combination with a pair of runners, of a base carried by said runners, interposed means for leveling said base with respect to said runners, said means having swiveled connections with said runners, a caisson on said base, means for raising and 45 lowering said caisson, a suction pipe extending through said caisson, and means for preventing the escape of air from said suction pipe.

50 12. The combination with a pair of runners, of a base carried by said runners, interposed means for leveling said base with respect to said runners, said means having swiveled connections with said runners, a 55 caisson on said base, means for raising and lowering said caisson, a suction pipe extending through said caisson, means for preventing the escape of air from said suction pipe, said means comprising a valve, and weighted 60 means for holding said valve against said suction pipe extremity.

13. The combination with a pair of runners, of a base carried by said runners, interposed means for leveling said base with respect to said runners, a caisson on said base,

means for raising and lowering said caisson, a suction pipe extending through said caisson, means for preventing the escape of air from said suction pipe, said means comprising a flexible valve adapted to fit the opening at 70 the extremity, of the pipe, weighted means on said valve arranged to hold said valve flush in said opening, and means for preventing the accidental opening of said valve.

14. The combination with a pair of runners, 75 of a base carried by said runners, interposed means for leveling said base with respect to said runners, a caisson on said base, means for raising and lowering said caisson, a suction pipe extending through said caisson, 80 means for preventing the escape of air from said suction pipe, said means comprising a flexible valve adapted to fit the opening at the extremity, of the pipe weighted means on said valve arranged to hold said valve flush 85 in said opening, and a pawl carried by said weighted means arranged to hold said valve in its normal position against the extreme opening of the suction pipe.

15. The combination with a pair of runners, 90 of a base, pivotal means interposed between said base and runners for supporting said base, a caisson carried by said base, said caisson comprising an inclosure, a water compartment within said inclosure, inlets 95 and outlets for said compartments, an air chamber between said water compartments, means for supplying air to said air chambers, a folding platform in the bottom of said caisson, and means for raising and lowering 100 the caisson.

16. The combination with a pair of runners and a base, of means for pivotally supporting said base on said runners, fluid pressure means for compensating for uneven- 105 nesses, a frame on said base, a caisson within said frame, said caisson being provided with racks, means for guiding said caisson in said frame, means for raising and lowering said caisson, means for controlling said means, 110 means for supplying air to said caisson, and a source of supply for said means.

17. The combination with a pair of runners and a base, of fluid pressure means interposed between said runners and base for 115 leveling said base with respect to said runners and forming a support for said base, a caisson carried by said base, means for supplying air to said caisson, means for raising and lowering said caisson, and means for controlling said means for raising and lowering 120 said caisson.

18. The combination with a pair of runners and a base, of fluid pressure means interposed between said runners and base for 125 leveling said base with respect to said runners and forming a support for said base, a caisson carried by said base, means for supplying air to said caisson, means for raising and lowering said caisson, and clutch mech- 130

- anism for controlling said raising and lowering means.
19. The combination with a pair of runners and a base, of fluid pressure means interposed between said runners and base for leveling said base with respect to said runners and forming a support for said base, a caisson carried by said base, means for supplying air to said caisson, means for raising and lowering said caisson, flexible means extending through said caisson and arranged to carry up by suction gravel and other fragments, and means for controlling the supply of air in said flexible means.
20. The combination with a base having mounted thereon an air compressor, an air tank, connections between said air tank and compressor, an electric generator, means for driving said generator, a caisson, connections between said air compressor and said caisson, of a pair of runners, means for pivotally mounting said base on said runners, and fluid pressure means for leveling said base independently of said runners.
21. The combination with a base having mounted thereon an air compressor, an air tank, connections between said air tank and compressor, an electric generator, means for driving said generator, a caisson, connections between said air compressor and said caisson, of a pair of runners, means for pivotally mounting said base on said runners, fluid pressure means for leveling said base independently of said runners, and take-up means for propelling said base and runners.
22. A caisson having a flexible apron at its end, and a ring for suspending said apron within said caisson.
23. A caisson having a flexible apron at its end, a ring for permanently securing it to one
- end of said caisson, and means for suspending the free end.
24. Runners, a base on said runners, a caisson carried by said base, means for causing said caisson to lower and rise, and means for leveling said base independently of said runners.
25. The combination with a plurality of runners, of a base carried by said runners, interposed means for raising and lowering said base with respect to said runners and independently thereof, a caisson on said base, and means for raising and lowering said caisson.
26. The combination of a pair of runners and a base, flexible connections between said base and runners, and means for raising and lowering said base independently of said connections.
27. A caisson having an extension at the bottom thereof, said extension being secured within said caisson and adapted to be swung beyond the extremity of the same and means for suspending said extension within the caisson.
28. The combination with a base and runners, of means interposed between said base and runners for leveling said base, a frame carried by said base, a caisson in said frame, means for raising and lowering said caisson, a suction pipe extending through said caisson, and means for preventing the escape of air from said suction pipe.
- In testimony whereof, I have hereunto set my hand at Los Angeles California this 21st day of September 1906.
